US00D686571S

(12) **United States Design Patent**
Hoyle(10) **Patent No.:** **US D686,571 S**
(45) **Date of Patent:** **** Jul. 23, 2013**(54) **THERMOELECTRIC GENERATOR FOR
POWERING AN EXTERNAL ELECTRICALLY
OPERATED DEVICE**(71) Applicant: **Richard Hoyle**, Clarkston, MI (US)(72) Inventor: **Richard Hoyle**, Clarkston, MI (US)(73) Assignee: **Tellurex Corporation**, Traverse City, MI
(US)(**) Term: **14 Years**(21) Appl. No.: **29/439,416**(22) Filed: **Dec. 11, 2012****Related U.S. Application Data**(63) Continuation-in-part of application No. 29/420,519,
filed on May 10, 2012, now abandoned.(51) **LOC (9) Cl.** ..... **13-01**(52) **U.S. Cl.**USPC ..... **D13/114**(58) **Field of Classification Search**USPC D13/114, 112, 113, 116, 122, 184,
D13/199; D15/1, 5; 290/36 R, 38 R, 39; 310/10,
310/20, 40 R, 40 MM, 42, 68 D, 75 R, 80,
310/83, 88, 89, 98, 109, 114

Primary Examiner — Derrick Holland(74) *Attorney, Agent, or Firm* — Flynn, Thiel, Boutell & Tanis, P.C.(57) **CLAIM**The ornamental design for a thermoelectric generator for
powering an external electrically operated device, as shown
and described.**DESCRIPTION**FIG. 1 is a top, front and left side isometric view of a thermo-
electric generator for powering an external electrically
operated device showing my new design;FIG. 2 is a front view thereof, the left, right, and rear side
views being a mirror image;

FIG. 3 is a top plan view thereof;

FIG. 4 is a bottom plan view thereof; and,

FIG. 5 is a bottom plan view thereof, with the broken lines for
the base removed for ease of illustration.The broken lines shown represent unclaimed subject matter
and form no part of the claimed design.**1 Claim, 5 Drawing Sheets**FIG. 1

FIG. 2

FIG. 3

FIG. 4

FIG. 5
